UNITED STATES PATENT OFFICE.

GEORGE CARRUTHERS ST. JOHN SNELL, OF BIRMINGHAM, ENGLAND, ASSIGNOR TO
J. B. BROOKS AND COMPANY LIMITED, OF BIRMINGHAM, ENGLAND, A BRITISH
COMPANY.

HAND BAG OR CASE.

Application filed August 7, 1926, Serial No. 127,764, and in Great Britain March 31, 1926.

This invention relates to suit-cases, blouse-cases and like hand bags or cases for containing personal belongings while traveling.

5 The object of the invention is to provide an improved construction of hand bag or case which is cheaper to manufacture and is lighter in weight than the usual leather suit-cases or the like, but which is nevertheless 10 strong and rigid in use.

According to the invention, the body of the bag or case is composed of a peripheral stiffening board set vertically on edge with the ends joined together, so as to form the 15 required shape, and made of suitable material, such as fibre-board, mill-board or the like, being covered upon the outside by oil-cloth, leather, or other flexible material; and the top and bottom of the said body are 20 reinforced by separate rigid frames corresponding in shape to the contour of the stiffening board, and secured to or engaged with the inside face of the latter, the top frame being held in place by turning over 25 the upper edge of the exterior covering on to the inside of the body and securing it thereto so as to overlap the said frame. The bottom frame may be held in place by the 30 inside lining of the bag, said lining being secured to the stiffening walls.

The top and bottom of the case may be of 35 flexible waterproof material without stiffening boards, the top being attached to the body at the back thereof so that it can be folded over to cover the mouth or top of the case, and preferably having a flexible flange by means of which it may be secured to the front of the body, and also, if necessary, to the sides, by means of suitable fastening 40 devices.

The lining for the vertical walls of the case is preferably first seamed to the junction of the bottom and vertical-wall external coverings, and then the stiffening boards 45 and metal frames are placed in position, and after the external covering has been turned over on to the inside face of the boards and secured thereto, the said lining is raised to cover the boards and cemented or otherwise 50 secured thereto immediately above the bot-

tom metal frame, so as to hold the latter in place, and also at the top edge, and at other parts if necessary.

Figure 1 of the accompanying drawings represents a perspective view of a lady's blouse or suit case constructed in accordance 55 with the present invention.

Figure 2 is a transverse section through the case, with the lid partly raised.

Figure 3 is a vertical section, upon a larger 60 scale, of the top edge of the body of the case, showing the reinforcing frame.

Figure 4 is a similar section through one of the bottom corners.

Figure 5 represents a horizontal section 65 through the body of the case, on line $x-x$, Figure 2, showing the contour of the peripheral stiffening board.

Figure 6 is a horizontal section on line x^1-x^1 , Figure 2, showing how the handle is 70 secured.

Figure 7 is an inside elevation of the rear side wall of the case with a portion of the lining removed, showing how the ends of the stiffening board overlap and are joined 75 together.

Figure 8 is a vertical section through one of the front corners of the lid, the body of the case being shown in elevation.

Figure 9 illustrates, in perspective, the 80 stiffening board and metal frames, before the case is made up.

Referring to Figures 1 to 9 of the drawings, the body of the case is of the usual 85 rectangular shape, and is composed essentially of a peripheral stiffening wall 1 of fibre-board, mill-board, or the like, set on edge, and covered externally with a covering 2 of oil-cloth, leather, imitation leather or other flexible and preferably waterproof material. This flexible covering 2 is in the form of a peripheral band continuous around the front, sides and back of the body, the ends preferably being stitched together at the back, as at 3, Figure 5. The lower edge 95 of this covering is seamed to a bottom piece 4 of similar waterproof flexible material, preferably by folding the edges of these parts inwards and stitching them together (see Figure 4), there being also included 100

in the seam an externally-disposed corded strip 5, as well as the adjacent edges of fabric linings 6, 7, for the bottom and sides of the interior of the body. The peripheral 5 stiffening board 1 is conveniently in the form of a strip of fibre-board, mill-board or the like, bent to the required rectangular shape (see Figures 5 and 9) with the ends overlapping at the back of the case and riveted together, as at 8. This rectangular frame or wall 1 is placed in a vertical position against the inside face of the outer covering 2 before the lining 7 of the side walls is raised and fastened in place. Thus 10 the said lining 7, being secured at its lower edge to the outer covering 2 and to the bottom 4, lies upon the latter while the stiffening board 1 is being inserted. To give the necessary rigidity to the case, two endless 15 steel frames or hoops, 9, 10, of rectangular form, and of circular or other convenient section, are placed within the body against the inside face of the stiffening board 1. The frame 9 is placed at the bottom of the case, 20 and the other 10 around the inside of the open top of the body, flush with the edge of the stiffening board. To secure this top frame 10 in place, the upper edge 11 of the exterior waterproof covering 2 is folded inwards over the top edge of the stiffening 25 board, so as to overlap the steel frame 9, and is cemented to the inside face of the board and to the frame. The lining 7 for the sides of the case is then raised over the 30 face of the stiffening board and is cemented thereto immediately above the bottom steel frame 9, and also at the top edge. By this means the bottom frame 9 is held in place and prevented from rising. Both frames 9, 35 10, may also be glued to the inside face of the stiffening board.

The lid or cover 12 of the case consists of a rectangular piece of oil-cloth, leather, or other flexible waterproof material, stitched along its rear edge at 13 to the back of the stiffening board 1, and provided at the front and sides with a continuous depending flexible flange 14 made of the same material and suitably seamed to the main portion, preferably with an externally-disposed corded strip 15 included in the seam. When the lid is closed this flange is adapted to be detachably secured to the body at the corners, or at other points, by means of turn-buttons, snap-fasteners, straps or other means. For example, as shown, the flange 14 may have stitched to the inside of the front corners tabs 16 made of flexible material and depending below the lower edge of the flange, these tabs carrying snap-fastener members 17 adapted to engage with co-operating fastener members 18 secured to the corners of the body. The tabs 16 serve to raise the lid, but to prevent the corners of the lid from being

buckled or crumpled when the tabs are lifted, the upper portions of the said tabs which are situated in the corners of the lid, are stiffened by means of strips 19 of fibre-board or the like secured between two thicknesses of material forming the tab, as shown in Figure 8.

A carrying handle 20 is secured to the front of the body, and in order to attach this firmly a metal strip 21 is riveted to the inside face of the stiffening board 1, while the attachment plates 22 for the handle are secured by rivets 23 passed through the body and through the said metal strip 21.

Having fully described my invention, what I desire to claim and secure by Letters Patent is:—

1. A hand travelling case comprising a body portion composed of a peripheral stiffening board set vertically on edge with the ends overlapping and joined together to form the required shape, separate top and bottom endless reinforcing frames corresponding in shape to the contour of the stiffening board and engaged with the inner face thereof, one adjacent the bottom and the other adjacent the top, an outer covering of flexible material the upper edge of which is turned over and secured to the inside face of the stiffening board so as to overlap the top reinforcing frame, and an inside lining covering the bottom reinforcing frame and secured to the inside face of the stiffening board.

2. A hand travelling case comprising a body portion composed of a peripheral stiffening board set vertically on edge with the ends overlapping and joined together to form the required shape, separate top and bottom endless reinforcing frames corresponding in shape to the contour of the stiffening board and engaged with the inner face thereof, an outer covering of flexible material the upper edge of which is turned over and secured to the inside face of the stiffening board so as to overlap the top reinforcing frame, a separate bottom made of flexible material and stitched to the outer covering, and a separate lid made of flexible material and attached to the back of the body, said lid having a flexible flange adapted to engage over the upper portion of the body.

3. A hand travelling case comprising a body portion composed of a peripheral stiffening board set vertically on edge, separate top and bottom endless reinforcing frames corresponding in shape to the contour of the stiffening board and engaged with the inner face thereof, an outer covering of flexible material the upper edge of which is turned over and secured to the inside face of the stiffening board so as to overlap the top reinforcing frame, a bottom made of flexible

material and attached to the outer covering, a lid made of flexible material and attached to the back of the body, said lid having a flexible flange adapted to engage over the upper portion of the body, depending tabs attached to the inside of the front corners of the flange, means for stiffening the upper portions of the tabs, fastener elements carried by the lower ends of the tabs, and operating fastener elements on the body. Signed at Birmingham, in the county of Warwick, England, this 16th day of July, 1926.

GEORGE CARRUTHERS ST. JOHN SNELL.
